CLAIM

The ornamental design for a teething mitt, as shown and described.

DESCRIPTION

FIG. 1 is a front perspective view of a teething mitt showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines illustrate portions of the teething mitt that form no part of the claimed design.
